Primary Examiner — Dana Meyrow(74) *Attorney, Agent, or Firm* — Fross Zelnick Lehrman & Zissu, P.C.; Charles T. J. Weigell, Esq.(57) **CLAIM**

What is claimed is the ornamental design for a bottle, as shown and described.

DESCRIPTION

FIG. 1 is a front perspective view of my new design shown in FIG. 1;

FIG. 2 is a front view thereof;

FIG. 3 is a back view thereof;

FIG. 4 is a side view thereof;

FIG. 5 is the other side view thereof; and,

FIG. 6 is a top view thereof.

The thicknesses of the bottle walls are not substantial and form no part of the claim.

The stippling indicates a contrasting opaque surface.

The broken line showing of the bottom portion of the bottle shows unclaimed subject matter for the design in those drawings.
